Primary Examiner—Jeffrey Asch

(74) Attorney, Agent, or Firm—Perman & Green, LLP

CLAIM

The ornamental design for a display and key array for a handset, as shown and described.

DESCRIPTION

FIG. 1 is a bottom plan view of a display and key array for a handset showing our new design;

FIG. 2 is a right side view thereof;

FIG. 3 is a front elevational view thereof;

FIG. 4 is a left side view thereof;

FIG. 5 is a top plan view thereof; and,

FIG. 6 is a front, bottom and right side perspective view thereof.

The dotted lines showing the outline of a telephone handset is for illustration purposes only and forms no part of the claimed invention.
